UNITED STATES PATENT OFFICE.

CHARLES SULZNER, OF PHILADELPHIA, PENNSYLVANIA.

DESIGN FOR A TROUSERS-GUARD.

SPECIFICATION forming part of Design No. 24,796, dated October 29, 1895.

Application filed May 2, 1895. Serial No. 547,936. Term of patent 7 years.

To all whom it may concern:

Be it known that I, CHARLES SULZNER, a citizen of the United States, residing in the city and county of Philadelphia, State of Pennsylvania, have invented and produced a new and original Design for a Trousers-Guard, of which the following is a specification, reference being had to the accompanying drawings, forming part thereof.

10 The leading feature of my design for a trousers-guard consists in jaws with diverging handles and diverging feet on the outer ends of said handles, the divergence of the feet being greater than that of the handles.

15 Figure 1 represents a perspective view of a trousers-guard embodying my design. Fig. 2 represents a side elevation thereof.

In the drawings, A designates jaws, which are pivoted together, as at B. C designates feet on the handle ends of said jaws, the same being continuous of said ends and diverging therefrom in the form of segments, it being noticed that said handles diverge from said jaws and said feet diverge from the outer ends of said handles, the divergence of the feet being greater than that of the handles.

What I claim is—

The design for a trousers guard, substantially as described and shown.

CHARLES SULZNER.
